CLOSURE

Raymond W. Barton, Evansville, Ind., assignor to
 Mead Johnson and Company, Evansville, Ind.,
 a corporation of Indiana

Application April 3, 1946, Serial No. 659,387

15 Claims. (Cl. 128—214)

1

This invention relates to a new and improved dispensing set for removing the contents of sterile liquid containers.

It is often desirable to remove sterile liquids from the original container over a continuous, extended period, particularly in the case of intravenous solutions. It also may be desirable to withdraw portions of the liquid at separate intervals, and to nevertheless keep the liquid uncontaminated during the process of removal, or in the intervening periods.

A means of measuring the rate of withdrawal of liquid withdrawn from a container is necessary or desirable, also, in numerous instances.

To keep such solutions sterile under these conditions it is necessary to provide a means of completely sealing the container after the liquid has been placed in it, and this seal must remain intact during the shipping and handling of the container, prior to the time any liquid is withdrawn.

It is, therefore, an object of this invention to provide a dispensing set that furnishes such a seal when properly placed on the container.

It is also an object of this invention to provide a dispensing set, the body of which may be constructed of any material desired without regard to possible contamination of the liquid. This is possible because the body of the closure disclosed is insulated completely from the liquid at all times by a resilient liner. This feature eliminates the possibility of contamination of the liquid by small particles of the material of which the body is constructed, which may have broken off during shipping and handling. One commonly used form of closure, for instance, has a body constructed of plastic material, which is not insulated from the liquid, and the incidence of contamination with small particles of the plastic is substantial. The disclosed dispensing set, on the other hand, allows a wide choice of materials for the body, such as a light metal, which would provide high strength and serviceability without fear of contamination either from contact or chipping.

It is a further object to provide a dispensing set which greatly reduces the possibility of breakage generally, since there is a minimum of protruding parts, and the body of the closure may be made of a material of great strength.

Another object of the invention is to provide a new and improved means for removing the liquid from the container without contaminating either the liquid so removed, or the liquid remaining in the container.

2

Another object of the invention is to provide a new and improved means for filtering the air allowed to replace the liquid removed from the container, that will function efficiently as long as there is liquid remaining in the container, and that is simple in construction and easily assembled during manufacture.

Another object of the invention is to provide a dispensing set which has a small number of parts to assemble during manufacture, and all of which are either held in position by friction alone, or by threaded engagement. This greatly simplifies the manufacturing procedure by eliminating cementing operations which are both time consuming and laborious, and which often result in a faulty seal. This, in turn, eliminates another possible source of contamination, both from such faulty seals or from the cementing material used.

Another object of the invention is to provide a dispensing set which allows the liquid to be removed from the container by gravity flow through a spout in the closure provided for that purpose, or by a needle, the needle being inserted into the container through a piercing area in the resilient liner of the closure provided for that purpose.

Another object of the invention is to provide a dispensing set which gives a visual indication of the rate of flow of the air into the container, as the liquid is being removed, which, in turn, is an indication of the rate of flow of the liquid out of the container. Present methods of indicating the rate of flow of the liquid require placing a drip-meter in the line of flow of the liquid after it leaves the container. Construction of such a drip-meter is relatively expensive and, therefore, they are generally re-used, after cleaning, which is relatively difficult.

Another object of the invention is to provide a dispensing set that eliminates the need for cleaning and sterilizing the indicator since it only comes into contact with the air replacing the liquid prior to the time the air enters the filtering medium in the closure.

In addition, it is a further object to provide a dispensing set of such simplicity that parts of it can be made up at a cost that permits single use and disposal of said parts.

Other objects and advantages will appear as the specification proceeds.

In the drawings—

Figure 1 is a vertical sectional view of the closure portion of the dispensing set with the removable cap and plug in place;

Figure 2 is a plan view of the same, viewed from above; and,

Figure 3 is a vertical sectional view of the dispensing set in operating position with the cap and plug removed and the indicator and dispensing hose in place.

Referring now to Figure 1, the closure 1 has substantially the form of a screw cap with the top portion 2 and the octagonal side wall 3 extending perpendicularly therefrom at its periphery. The side wall 3 has the threads 4 on its inner surface for engaging similar threads on the container (not shown) on which the closure is placed. The cylindrical filter holder 5, having the cylindrical passage 6 therethrough, is an integral part of the top portion 2, and extends therefrom on both sides. The lip of the container, when the closure is screwed on, fits tightly against the outer edge of the resilient liner 7, which encloses the side of the top portion 2 and the end 8 of the filter holder 5, adjacent to the container.

The liner 7 is so shaped as to form the well 9 coaxial with the end 8 of the filter holder 5, which it encloses. The cup 10 is placed in the well 9 with its base 11 adjacent the end 8 of the filter 5, and with its open end 12 adjacent the bottom 13 of the well 9. The lip 14 of the cup 10 is formed with the slotted openings 15 to prevent the cup from becoming sealed against the bottom 13 of well 9, and the side walls 16 and base 11 of the cup have the corresponding grooves 17 to allow a free passage of air around the outside of the cup.

The tube 18 is held at its flared end 19 in the opening 20 in the bottom 13 and extends outwardly therefrom, away from the open end 12 of the cup 10 on the axis of the passage 6. As shown in Figure 3, the tube 18 terminates in the valve 21, commonly known as a Bunsen valve, formed of resilient material and having the longitudinal slit 22. The valve operates to allow the flow of air from the tube, but prevents a flow of liquid or air in the opposite direction into the tube. It thus serves to keep the tube 18 free from liquid at all times.

The filter holder 5 is filled with the air-filtering medium 23, such as cotton or similar material, which must be kept free from moisture for satisfactory operation. The valve 21, as explained above, operates to prevent any moisture from entering the tube 18, and the cup 10 is provided as a secondary measure in the form of a trap to prevent any moisture that might enter the tube 18 from reaching the air-filtering medium 23 when the container is inverted preparatory to withdrawing liquid from it.

The other protruding end 24 of the filter holder 5 has at its termination the threads 25 which engage the threads 26 of the removable cap 27 when it is in place. The cap 27 has the resilient washer 28 seated on the inner surface of its top 29, and seals the opening of the passage 6 in the end 24 when the cap 27 is threaded tightly onto the end 24.

The top portion of the closure 1 also has the opening 30, through which the spout 31 extends, its open end being flush with the outer surface of the top 2. The spout 31 is an integral part of the resilient liner 7, and, as shown in Figure 1, the outer diameter of the spout is less than that of the opening 30, which permits the spout to expand or flex, when necessary. The T-shaped plug 32 is inserted in the center opening 33 in the spout 31, and because of the resilient character of the liner material, forms a tight seal, but is also readily removed when desired.

To insure that the plug 32 remains firmly seated during shipping and handling, the cap 27 is so formed that its bottom edge 34 engages the upper edge 35 of the plug 32 when the cap 27 is threaded onto the end 24 of the filter holder 5, as shown in Figures 1 and 2. This feature also tends to prevent improper operation of the dispensing set, since proper use requires that the cap 27 be removed prior to the removal of the plug 32. With cap 27 locking the plug 32 in place, it is difficult, if not impossible, to remove the latter without first having removed the former. Since there may be a reduced pressure inside the container at the time it is unsealed, it is desirable to first break the seal at the end 24 of the filter holder passage 6, so that any air entering the container to relieve the reduced pressure will first pass through the filter medium 23.

The additional opening 36, as shown in Figures 1, 2 and 3 in the top portion 2 of the closure 1 is sealed with a portion 37 of the resilient liner 7 molded to fit the opening and extending through the opening to a point substantially flush with the outer surface of the top portion 2. This exposed portion of the resilient liner 7 has a small, raised ring portion 38 substantially in the center of the exposed surface. This ring portion defines the piercing area 39 in the resilient liner, through which a needle may be inserted to withdraw a portion of the liquid. This feature of the closure is distinctly new and provides greater flexibility in the use of the container and the liquid contained therein.

Referring now to Figure 3, the closure is shown in operating position for removal of the liquid by gravity flow through the dispensing hose 40. To prepare the container for removal of the liquid in this manner, the cap 27 is removed from the end 24 of the filter holder 5, and the plug 32 is then removed from the spout opening 33. The hose 40 and the nozzle adaptor 41 have previously been sterilized with the end of the hose 40 slipped over the end 42 of the adaptor 41. The usual precautions commonly used in handling sterile equipment should be observed while making the connection, and also in inserting the other end of the adaptor 43 into the opening 33 in the spout 31, which is the next step.

The container is inverted and supported in this position, and the liquid will then flow freely from the container, through the hose 40, and the rate of flow may be adjusted or completely stopped by manipulation of the usual screw compressor (not shown) placed on the hose 40. The rate of flow may also be controlled, to a degree, by adjusting the height at which the container is supported.

Satisfactory control of the rate of flow necessitates having some means of determining what the rate of flow is, other than noting the gradual change in the level of the liquid in the container. Much more accurate determinations are needed in the use of such equipment than would be possible from noting such changes. It is common practice to place what is known as a drip-meter in the line of flow of the liquid being dispensed. This device gives a visual indication of the rate of flow by enabling the operator to count the number of drops passing through the dispensing hose in a given mount of time.

The disadvantage in using this device is obvious, in that it introduces another possible source of contamination. This disadvantage is

5

enhanced by the fact that construction of the drip-meter is such that its manufacture is a relatively expensive process, and for this reason it is generally re-used for subsequent dispensing operations after a cleaning and sterilization procedure. Because of its construction, such a device is difficult to clean properly, and contamination may frequently occur.

To overcome this difficulty, the disclosed dispensing set includes the rate of flow indicator 44 constructed of some suitable, transparent material, being substantially cylindrical in shape, and having the internal bore 45. The threads 46 at the open end 47 of the bore 45, engage the threads 25 on the end 24 of the filter holder 5. The resilient washer 48 rides on the shoulder 49 immediately below the threads 46 at the end 47 of the bore 45, and provides an air-tight seal between the indicator 44 and the filter holder 5 when the indicator is threaded tightly onto the filter holder.

Extending from the bore 45, through the side wall 50 near the closed end of the bore 51, is the air inlet tube 52. Emerging from the side wall 50, the tube 52 bends toward the open end 47 of the bore 45 and extends a short distance in that direction substantially parallel to the longitudinal axis of bore 5.

Either prior to threading the indicator onto the closure, or after it is so disposed, a small amount of indicator liquid 53 is placed in the bore 45 and the inlet tube 52. The amount of liquid that can be held by the bore is automatically limited by the construction of the inlet tube 52, when the indicator 44 is in a vertical position. This regulation of the level of the indicator liquid is desirable since it prevents any creeping of the indicator liquid upward and subsequent wetting of the filtering medium. After the indicator is threaded onto the closure, any air drawn into the container by a flow of the liquid from the container must necessarily pass through the inlet tube 52, the indicator liquid 53, the indicator bore 45, the filtering medium 23, the well 9, the tube 18, the valve 21, and out through the slit 22 into the container.

The air passing through the indicator liquid 53 will appear in the form of bubbles 54, and the rate of flow of air into the container can be determined by counting the number of bubbles passing through the indicator liquid in a given period. Since the flow of air into the container is directly proportional to the flow of liquid out of the container, the bubble count gives an accurate indication of the rate of flow of the liquid.

Any suitable liquid can be used in the indicator, such as distilled water. If desired, a sterilizing liquid such as ethyl alcohol may be utilized as an indicator liquid which would furnish a partial sterilization of the air prior to its passage through the filtering medium.

It has been found that this type of indicator can be used to best advantage when the inside of the tube 18 is completely dry. This dry state is assured by the operation of the valve 21 as explained above.

It will be noted that the individual parts of the closure are so designed that assembling them to form the complete closure can be simply and inexpensively done. The resilient liner 7 may be molded of rubber or other suitable material and the tube 18 forced into the opening 20 in the base 13 of the well 9. The cup 10 may then be dropped in place in the well 9. This subassembly is then

6

force-fitted onto the main body of the closure, the tapered outer surface of the end 8 of the filter holder 5 acting as a guide, and as a frictional surface for retaining the liner. The liner is also frictionally held around its outer edge by the circular side walls 3. Consequently, there are no cementing operations involved in constructing the closure.

The additional equipment making up the dispensing set is also of simple construction and can be manufactured inexpensively, so that the complete set, except the "bubble-meter," may be furnished at a cost which permits single use and disposal, which procedure is highly desirable in the handling of sterile liquids.

The foregoing description of one embodiment of the invention is not intended to limit the invention to the particular details disclosed, for it may be embodied in other forms without departing from the spirit of the invention as defined in the following claims.

I claim:

1. A dispensing set for sterile liquid containers comprising, in combination, a closure body having means for engaging and sealing a container, a filter holder formed as an integral part of said body, projecting outwardly from both sides of said body and having a passage therethrough, said passage containing means for filtering air, a resilient liner substantially covering the side of said closure body associated with said container when said container is engaged, a tube associated with the end of said passage enclosed by said liner, said tube extending through said liner, means associated with said tube and passage preventing said liquid from entering said passage, means for dispensing said liquid from said container through said closure body, and means for measuring the rate of flow of air into said container as said liquid is dispensed.

2. A dispensing set for sterile liquid containers comprising, in combination, a closure body having means for engaging and sealing a container, a filter holder formed as an integral part of said body, projecting outwardly from both sides of said body and having a passage therethrough, said passage containing means for filtering air, a resilient liner substantially covering the side of said closure body associated with said container when said container is engaged and covering the projecting portion of said filter holder on said side, a well formed by said liner adjacent to the end of said projecting portion of said filter holder, a cup in said well disposed with its base adjacent the end of said filter holder, a tube associated with the open end of said cup extending through said liner and terminating in means permitting a flow of air in a direction away from the filter holder but preventing entry of the liquid into said tube, means for dispensing said liquid from said container through said body closure, and means for measuring the rate of flow of air into said container as said liquid is dispensed.

3. A dispensing set for sterile liquid containers comprising, in combination, a closure body having means for engaging and sealing a container, a filter holder formed as an integral part of said body, projecting outwardly from both sides of said body and having a passage therethrough, said passage containing means for filtering air, a resilient liner substantially covering the side of said closure body associated with said container when said container is engaged and covering the projecting portion of said filter holder on said side, a well formed by said liner adjacent to the

end of said projecting portion of said filter holder, a cup in said well disposed with its base adjacent the end of said filter holder, a tube associated with the open end of said cup extending through said liner and terminating in means permitting a flow of air in a direction away from the filter holder but preventing entry of the liquid into said tube, an opening in said closure body exposing a portion of said liner, said portion having the form of an open spout leading from the liner side of said closure body through said closure body to the opposite side, a removable plug inserted from said opposite side sealing said spout, said plug being locked in place by a removable cap sealing the end of the filter holder projecting from said opposite side.

4. A dispensing set for sterile liquid containers comprising, in combination, a closure body having means for engaging and sealing a container, a filter holder formed as an integral part of said body projecting outwardly from both sides of said body and having a passage therethrough, said passage containing means for filtering air, a resilient liner substantially covering the side of said closure body associated with said container when said container is engaged and covering the projecting portion of said filter holder on said side, a well formed by said liner adjacent to the end of said projecting portion of said filter holder, a cup in said well disposed with its base adjacent the end of said filter holder, a tube associated with the open end of said cup extending through said liner and terminating in means permitting a flow of air in a direction away from the filter holder but preventing entry of the liquid into said tube, an opening in said closure body exposing a portion of said liner said portion having the form of an open spout leading from the liner side of said closure body through said closure body to the opposite side, a removable plug inserted from said opposite side sealing said spout, said plug being locked in place by a removable cap sealing the end of the filter holder projecting from said opposite side, an adaptor for replacing said removable plug providing an extended outlet for said liquid, and means for measuring the rate of flow of air into the container when said liquid is dispensed.

5. A dispensing set for sterile liquid containers comprising, in combination, a closure body having means for engaging and sealing a container, a filter holder formed as an integral part of said body, projecting outwardly from both sides of said body and having a passage therethrough, said passage containing means for filtering air, a resilient liner substantially covering the side of said closure body associated with the said container when said container is engaged and covering the projecting portion of said filter holder on said side, a well formed by said liner adjacent to the end of said projecting portion of said filter holder, a cup in said well having a corrugated outer surface disposed with its base adjacent the end of said filter holder, a tube associated with the open end of said cup extending through said liner and terminating in means permitting a flow of air in a direction away from the filter holder but preventing entry of the liquid into said tube, an opening in said closure body exposing a portion of said liner and being completely sealed by same, an additional opening in said closure body exposing an additional portion of said liner, said additional portion having the form of an open spout leading from the liner side of said closure body through said closure body to the opposite side, a remov-

able plug inserted from said opposite side sealing said spout, said plug being locked in place by a removable cap sealing the end of the filter holder projecting from said opposite side, an adaptor for replacing said removable plug providing an extended outlet for said liquid, and means for measuring the rate of flow of air into the container when said liquid is dispensed.

6. A dispensing closure for sterile liquid containers comprising a closure body having means for engaging and sealing a container, a filter holder formed as an integral part of said body projecting outwardly from both sides of said body, and having a passage therethrough, said passage containing means for filtering air, a resilient liner substantially covering the side of said closure body associated with said container when said container is engaged and the projecting portion of said filter holder on said side, a well formed by said liner adjacent to the end of said projecting portion of said filter holder, a cup in said well having a corrugated outer surface, disposed with its base adjacent the end of said filter holder, a tube associated with the open end of said cup extending through said liner and terminating in means permitting a flow of air in a direction away from the filter holder but preventing entry of the liquid into said tube, an opening in said closure body exposing a portion of said liner and being completely sealed by same, an additional opening in the closure body exposing an additional portion of said liner, said additional portion having the form of an open spout leading from the liner side of said closure body through said closure body to the opposite side, a removable plug inserted from said opposite side sealing said spout, said plug being locked in place by a removable cap sealing the end of the filter holder projecting from said opposite side, an adaptor for replacing said removable plug providing an extended outlet for said liquid, an indicator replacing said removable cap on said filter holder when said liquid is being dispensed, said indicator being substantially a transparent extension of said filter holder and having an L-shaped air inlet at its closed outer extremity extending outwardly and then upwardly from the said indicator when said container is inverted, and being so disposed that a small amount of indicator liquid may be introduced into said indicator so that air entering said filter holder must first pass through said air inlet and through said liquid in said indicator.

7. A device of the character described comprising, in combination, a closure body having means thereon for engaging a liquid container for securing said body thereto in sealing relation, said body being provided with a filter holder, projecting toward and away from the container, said filter holder having a passage therethrough, a filter in said passage, a removable closure for the end of said filter holder extending away from the container, a resilient liner disposed in said body and having a portion adapted to be disposed between the container and a portion of the body whereby when said body is in engagement with the container said portion of said liner acts as a seal, said liner having a well member aligned with and embracing the portion of said body filter holder extending toward the container whereby a well is formed between said well member and said filter holder, a cup member disposed in said well having the cup portion facing said well member, a vent tube extending through a portion of said well member and communicating with said cup member, said cup member having a passage for

the depth of said cup member permitting communication between said vent tube and filter, and means extending through said liner for permitting discharge from the container.

8. A device of the character described, comprising, in combination, a closure body having means thereon for engaging a liquid container for securing said body thereto in sealing relation, said body being provided with a filter holder projecting toward and away from the container, said filter holder having a passage therethrough, a filter in said passage, a removable closure for the end of said filter holder extending away from the container, a resilient liner disposed in said body and having a portion adapted to be disposed between the container and a portion of the body whereby when said body is in engagement with the container said portion of said liner acts as a seal, said liner having a well member aligned with and embracing the portion of said body filter holder extending toward the container, whereby a well is formed between said well member and said filter holder, a cup member disposed in said well having the cup portion facing said well member, a vent tube extending through a portion of said well member and communicating with said cup member, said cup member having a passage for the depth of said cup member permitting communication between said vent tube and filter, said liner having a portion extending through said body, and means extending through said last named portion for permitting discharge from the container.

9. A device of the character described comprising, in combination, a closure body having means thereon for engaging a liquid container for securing said body thereto in sealing relation, said body being provided with a filter holder projecting toward and away from the container, said filter holder having a passage therethrough, a filter in said passage, a removable closure for the end of said filter holder extending away from the container, a resilient liner disposed in said body and having a portion adapted to be disposed between the container and a portion of the body whereby when said body is in engagement with the container said portion of said liner acts as a seal, said liner having a well member aligned with and embracing the portion of said body filter holder extending toward the container whereby a well is formed between said well member and said filter holder, a cup member disposed in said well having the cup portion facing said well member, a vent tube extending through a portion of said well member and communicating with said cup member, said cup member having a passage for the depth of said cup member permitting communication between said vent tube and filter, said liner having a spout extending through said body, and a closure for said spout adapted to be held in closed position by said first named closure.

10. A device of the character described comprising, in combination, a closure body having means thereon for engaging a liquid container for securing said body thereto in sealing relation, said body being provided with a filter holder projecting toward and away from the container, said filter holder having a passage therethrough, a filter in said passage, a removable closure for the end of said filter holder extending away from the container, a resilient liner disposed in said body and having a portion adapted to be disposed between the container and a portion of the body whereby when said body is in engagement with the container said portion of said liner acts as a seal, said liner having a well member aligned with

and embracing the portion of said body filter holder extending toward the container whereby a well is formed between said well member and said filter holder, a cup member disposed in said well having the cup portion facing said well member, a vent tube extending through a portion of said well member and communicating with said cup member, said cup member having a passage for the depth of said cup member permitting communication between said vent tube and filter, said liner having a spout extending through said body, a closure for said spout adapted to be held in closed position by said first named closure, said liner having a portion extending through said body, and means extending through said last named portion for permitting discharge from the container.

11. A device of the character described comprising, in combination, a closure body having means thereon for engaging a liquid container for securing said body thereto in sealing relation, said body being provided with a filter holder, said filter holder having a passage therethrough, a filter in said passage, a removable closure for the outer end of said filter holder, a resilient liner disposed in said body and having a portion adapted to be disposed between the container and a portion of the body whereby when said body is in engagement with the container said portion of said liner acts as a seal, said liner having a well member aligned with and embracing the inner end of said filter holder whereby a well is formed between said well member and said filter holder, a cup member disposed in said well having the cup portion facing said well member, a vent tube extending through a portion of said well member and communicating with said cup member, said cup member having a passage for the depth of said cup member permitting communication between said vent tube and filter and means extending through said liner for permitting discharge from the container.

12. A device of the character described comprising, in combination, a closure body having means thereon for engaging a liquid container for securing said body thereto in sealing relation, said body being provided with a filter holder, said filter holder having a passage therethrough, a filter in said passage, a removable closure for the outer end of said filter holder, a resilient liner disposed in said body and having a portion adapted to be disposed between the container and a portion of the body whereby when said body is in engagement with the container said portion of said liner acts as a seal, said liner having a well member aligned with and embracing the inner end of said filter holder whereby a well is formed between said well member and said filter holder, a vent tube extending through a portion of said well member and communicating with said filter, and means extending through said liner for permitting discharge from the container.

13. A device of the character described comprising, in combination, a closure body having means thereon for engaging a liquid container for securing said body thereto in sealing relation, said body being provided with a filter holder, said filter holder having a passage therethrough, a filter in said passage, a removable closure for the outer end of said filter holder, a resilient liner disposed in said body and having a portion adapted to be disposed between the container and a portion of the body whereby when said body is in engagement with the container said

portion of said liner acts as a seal, said liner having a well member aligned with and embracing the inner end of said filter holder whereby a well is formed between said well member and said filter holder, a vent tube extending through a portion of said well member and communicating with said filter, said liner having a portion extending through said body, and means extending through said last named portion for permitting discharge from the container.

14. A device of the character described comprising, in combination, a closure body having means thereon for engaging a liquid container for securing said body thereto in sealing relation, said body being provided with a filter holder, said filter holder having a passage therethrough, a filter in said passage, a removable closure for the outer end of said filter holder, a resilient liner disposed in said body and having a portion adapted to be disposed between the container and a portion of the body whereby when said body is in engagement with the container said portion of said liner acts as a seal, said liner having a well member aligned with and embracing the inner end of said filter holder whereby a well is formed between said well member and said filter holder, a vent tube extending through a portion of said well member and communicating with said filter, said liner having a spout extending through said body, and a closure for said spout adapted to be held in closed position by said first named closure.

15. A device of the character described comprising, in combination, a closure body having means thereon for engaging a liquid container for

securing said body thereto in sealing relation, said body being provided with a filter holder, said filter holder having a passage therethrough, a filter in said passage, a removable closure for the outer end of said filter holder, a resilient liner disposed in said body and having a portion adapted to be disposed between the container and a portion of the body whereby when said body is in engagement with the container said portion of said liner acts as a seal, said liner having a well member aligned with and embracing the inner end of said filter holder whereby a well is formed between said well member and said filter holder, a vent tube extending through a portion of said well member and communicating with said filter, said liner having a spout extending through said body, a closure for said spout adapted to be held in closed position by said first named closure, said liner having a portion extending through said last named portion for permitting discharge from the container.
